(57) **CLAIM**

The ornamental design for a boot with ankle brace, as shown and described.

DESCRIPTION

FIG. 1 is a top front perspective view of a boot with ankle brace showing the design.

FIG. 2 is a bottom rear perspective view thereof.

FIG. 3 is a top rear perspective view thereof.

FIG. 4 is a bottom front perspective view thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof; and,

FIG. 10 is a bottom plan view thereof.

The dashed lines shown in the drawings indicate portions of the boot with ankle brace that form no part of the claimed design. The shading lines shown in the drawings represent the approximate three-dimensional contour of the claimed design and are not intended to indicate surface decoration.
